(57) **CLAIM**

We claim the ornamental design for a template for a prescription medicine container, as shown and described.

DESCRIPTION

FIG. 1 is top perspective view of a template for a prescription medicine container according to one embodiment of the invention.

FIG. 2 is bottom perspective view of the template of FIG. 1.

FIG. 3 is a top view of the template of FIG. 1.

FIG. 5 is a rear view of the template of FIG. 1.

FIG. 6 is a front view of the template of FIG. 1.

FIG. 7 is a left side view of the template of FIG. 1; and, FIG. 8 is a right side view of the template of FIG. 1.

The portions of the template shown in broken lines are included for the purpose of illustrating environment and form no part of the claimed design. The portion of the template shown in broken lines having unequal length segments illustrate the boundary of the claimed design and form no part of the claimed design.
